UNITED STATES PATENT OFFICE.

HERMANN LEMP, OF LYNN, MASSACHUSETTS, ASSIGNOR, BY MESNE ASSIGNMENTS, TO
GENERAL ELECTRIC COMPANY, A CORPORATION OF NEW YORK.

KEROSENE-BURNER.

No. 926,883.

Specification of Letters Patent.

Patented July 6, 1909.

Application filed June 10, 1903. Serial No. 160,848.

To all whom it may concern:

Be it known that I, HERMANN LEMP, a citizen of the United States, residing at Lynn, county of Essex, State of Massachusetts, have invented certain new and useful Improvements in Kerosene-Burners, of which the following is a specification.

In operating kerosene burners for power-generating systems utilizing large quantities of oil at high pressure it is of the utmost importance that the liquid fuel shall enter the vaporizer at its coolest point and gradually increase in temperature to the burner opening. In this manner all danger due to carbonization or "cracking" is eliminated. Under certain conditions, such for example as in stopping while the parts are very hot, and at the same time greatly reducing the size of the burner opening, there is a tendency for the burner to pulsate. This is due to the fact that the high pressure on the vapor causes the column of liquid to surge back and forth in the supply pipe and permit the liquid oil to come in contact with the very hot surface of the vaporizer, thus suddenly and greatly increasing the pressure and increasing the surging. A burner will also pulsate if liquid fuel is entrained with the vapor and permitted to strike on a very hot surface, because the vapor pressure is thereby suddenly and greatly increased. Pulsating is objectionable chiefly because it is liable to extinguish the flame when a minimum amount of fuel is being used, and also because of the disagreeable noise accompanying it.

I have discovered that I can improve the operation of kerosene burners and also obviate pulsating by providing two or more vaporizers and connecting them in multiple to deliver vapor to a single burner opening of relatively restricted area. The liquid fuel is supplied simultaneously to the vaporizers at their coolest points and gradually increases in temperature to the point of delivery. By providing vaporizers and connecting them as described, the tendency of one vaporizer to cause pulsation is opposed by the other. To state it in a different way the pulsations in the two vaporizers, instead of being in phase or assisting each other, are bucking or opposing one another, and as a result the effect on the burner is practically *nil*. This arrangement further has the advantage of providing an enlarged vaporizing surface

which is capable of supplying the maximum amount of superheated vapor necessary for operation.

Some objection is raised to starting a kerosene burner with kerosene on account of the length of time required, and also on account of the disagreeable odor incident thereto. I have provided a means whereby the burner when used with an automobile or other boiler may be started in the stable or building containing the vehicle or other mechanism without loss of time and without objectionable odor. In carrying out this feature of my invention an auxiliary gas burner is provided that forms a permanent part of the main burner, and can, by means of a flexible pipe, be connected to a suitable source of gas supply. The auxiliary gas burner is so arranged that the flames therefrom heat a vaporizing tube or tubes on the main burner. After the proper temperature is reached the kerosene oil is admitted in the usual way, and the necessary vapor is generated. For starting the burner out of doors, or where gas is not obtainable, a starting wick is employed which is fed from the main supply of kerosene. The auxiliary burner and wick can be used in conjunction or separately.

Certain other features of my invention will be more fully set forth hereinafter.

In the accompanying drawings, which represent one embodiment of my invention, Figure 1 represents a side elevation of a burner with certain of its parts in section; Fig. 2 is a view in elevation taken at right angles to that shown in Fig. 1 with the inclosing casing in section; Fig. 3 is a plan view of the burner; Fig. 4 is a detail showing means for starting the main burner; and Fig. 5 is a diagram showing the way the vaporizers are connected.

In the drawing, 1 represents a suitable casing that surrounds the burner and also the boiler tubes (not shown) which are supported by the laterally extending tubes 2 that are attached to the side walls of the casing. The lower end of the casing is closed in by a plate, base or cover 3. The plate and also the inner walls of the casing are lined with asbestos or other heat-insulating material 4.

In order to prevent pulsations of the burner, and also to provide an enlarged vaporizing surface for the liquid fuel, vaporizers 5 and 6 are provided which rise vertically.

cally at right angles from the bottom plate 3 for a short distance, and then incline toward each other.

I do not wish to be understood as limiting 5 myself to any specified number of vaporizers, the essential feature being to have them arranged to deliver to a common point so as to prevent pulsation.

The vaporizers are united by a head 7 at a 10 point directly over the burner opening, and are preferably made out of steel, as I have found that cast iron, when used for this purpose, pits, owing to the chemical action of the kerosene vapor on the iron; and this pitting 15 causes the vaporizer to fill with sediment. The object in inclining the tubes is to prevent, as far as possible, the entraining of the liquid with the vapor, and by this arrangement the active surface of the vaporizer 20 is automatically varied as the burner flame varies. That is to say, when the flame is small the upper portions only of the tube are hot, but as the pressure on the vapor system increases the flames will strike or 25 envelop more and more of the inclined tubes, and the area or zone of heated metal will be increased. The lower ends of the tubes are screw-threaded to supports 8, which are attached to the base plate in any suitable manner. It is to be noted that the lower end of 30 each tube is surrounded by a casing 9, that is filled with some material which is a non-conductor of heat. The object of this arrangement is to maintain as great a temperature 35 difference as possible between the oil within the vaporizer and that in the supply pipes. The supports 8 are connected to the supply pipes in a manner to be hereinafter described. I have found it advantageous to 40 make the head or union 7 between the two tubes out of forged steel, and to electrically weld the tubes 5 and 6 thereto, so as to avoid leaky joints.

To the under side of the connector 7 is detachably secured a baffle plate 10 comprising a horizontally-extending head having a smooth and slightly beveled under surface against which the vapor in a solid stream or column is projected and diverted laterally 50 toward the vaporizing tubes, at the same time causing it to mix with the proper amount of air to support combustion. Extending upwardly above the baffle plate is a screw-threaded shank or steel whereby it is attached to the head 7. Intermediate the nozzle and vaporizers the vapor stream is 55 deflected by the baffle plate, the said stream entraining air to make a highly inflammable mixture, as it is to about leave or after it leaves the periphery of the baffle plate. Between the periphery of the baffle plate and the adjacent surfaces of the vaporizers the vapor is ignited. This ignition can take 60 place only after the vapor has been spread by the deflector to cause it to mix with suffi-

cient air to support combustion. The space immediately surrounding the nozzle and baffle plate may be divided into two parts, which I term the carbureting and combustion zones, which zones are concentric. The 70 space between the end of the nozzle and the deflector may also be said to be a part of the carbureting zone. To state the matter in a different way, there is a zone extending from the nozzle orifice to the baffle plate and for a 75 short distance below the baffle plate and around the baffle plate, in which the air is mixed with the vapor, and outside of this zone and surrounding it is a zone in which combustion takes place. The vapor leaves 80 the burner orifice under high velocity and if the baffle plate is too near or too far from the end of the nozzle the flame will be yellow and give off smoke, thus rendering the burner useless for the purpose intended. Moreover, 85 under such conditions the heat produced by the burner is greatly decreased. I have found that if the baffle plate is suddenly removed and there is nothing to act as a baffle, the flame will go out due to the high 90 velocity of the vapor stream. By experiment I have determined that the space between the end of the nozzle and the baffle plate should not be more than one and one-half inches or less than three-fourths of an 95 inch to obtain the best results, and further that the vaporizers must be in a position to be affected by the blue flame of the burning mixture. It follows therefore that the carbureting and combustion zones must and do 100 bear a definite relation to the baffle plate and vaporizers, and in these matters my improved burner differs from others. I have found by a series of careful experiments that the most satisfactory metal to use for these 105 baffle plates is pure nickel. It must be smooth on the under side, or the side presented to the nozzle opening. The baffle-plate being of nickel will maintain its original smoothness irrespective of the velocity of 110 vapor jet and the degree of temperature of the vapor without becoming pitted or roughened as has been found to be the case with various other metals after a short period of use.

Secured to the base or plate 3 is a tray 11 115 which surrounds the vertically-extending tube 12 that carries the burner nozzle 13. The nozzle is made detachable, and is provided with a single opening of relatively restricted area. The object in providing the 120 tray 11 is to catch the oil which overflows from the nozzle in starting and permit the wick 29 to absorb it. The nozzle-carrying tube contains a rod 14 which carries the needle 15. The latter is intended to enter 125 the opening in the nozzle 13 and restrict the amount of vapor delivered thereby. The needle is not intended to completely close the nozzle or burner opening at any time, but to act only as a restriction. The lower 130

end of the rod 14 is provided with a suitable stuffing-box to prevent vapor escaping at this point. Situated below the base plate is a support 16 in which is pivoted the arm 17 that actuates the needle.

Referring to Fig. 2, it will be seen that the head or union 7, between the vaporizing tubes, is connected to a U-shaped pipe or tube 18, the latter being connected to the tube 12 that carries the burner nozzle. The tube 18 can, with advantage, be covered by a non-conducting covering at the portions which lie in the combustion zone of the main burner so as to prevent overheating. This tube is of smaller size and hence more easily heated than the vaporizing tubes 5 and 6, so as to insure the proper vaporization of the fuel before it enters the burner. The lower portion of the tube which is not covered, 20 extends parallel with the base and with an extension on the tray 11. In the extension of the tray is provided the wick 29 that may be used for starting the burner into operation by flooding the tray with kerosene oil 25 from the burner nozzle 13. In addition to this a separate or auxiliary means is provided, whereby the burner can be started into operation by the use of ordinary illuminating gas when it is desired to make a quick 30 start, and the objectionable odor incident to starting with kerosene is obviated. This auxiliary starting means, best shown in Fig. 3, comprises a tube 20, which is U-shaped and is closed at one end, and adapted to be 35 connected to a source of supply at the other. The adjacent portions of the tube are provided with holes 21 for permitting the gas to escape. The tube is provided with an extension 22, Fig. 2, to which a piece of rubber 40 hose can be attached. Under ordinary conditions this starting device is used only when the vehicle or other apparatus to which the burner is attached can be connected to a suitable source extraneous to the vehicle, 45 as for instance a gas pipe connected with the city main. The side of the casing is provided with a hinged door 23, by means of which a match can be inserted to start the auxiliary burner into operation.

50 Referring to Figs. 3 and 5, kerosene in liquid form enters the first vaporizer by the pipe 24, which pipe is also extended as at 55 to the second vaporizing tube 6. Between the two vaporizers is a coupling 26 by means of which one of the vaporizers can be cut out of service if desired, and it also facilitates the assembling and repairing of the parts. Connected to the vaporizers by a pipe 27 is a gage 28, for indicating the 60 pressure on the fuel system.

In Fig. 4 the tray 11 is shown in position under the lower portion of the U-shaped gas-burner tube 20. Extending downwardly from the sides of the tray and through an 65 opening in the base plate is the wick 29, by

means of which the regular starting device can be put into operation.

In order to support combustion, it is necessary to admit air to the lower part of the casing. This has been commonly done 70 by making holes in the sides of the casing and providing deflector plates which directed the air currents downward to a point below the burner nozzle, so that the air and vapor would properly mix. I have found that 75 while this acts to direct the air currents downwardly, it is unsatisfactory, in that it permits of cross drafts. That is to say, a blast of wind will strike one side of the casing and cause air currents to pass through 80 the opening across the bottom of the casing and out the openings on the opposite side. This action also causes the burner flame to pass through the openings on the side opposite to that from which the blast comes 85 and burn the body of the vehicle. I propose to overcome this objectionable feature by a novel arrangement of deflector plates, whereby cross-drafts are prevented, yet the proper amount of air is caused to mingle 90 with the vapor.

The sides of the casing are closed, and extending therefrom are inwardly inclined deflector plates 30. These plates can, with advantage, be attached to the side walls of the 95 casing, although any other convenient support can be employed. Openings 32 are provided in the bottom plate of the casing which are situated directly under the projecting ends of the plates. Between the end 100 of each plate and the adjacent side wall is located a second deflector plate 31 over-lapping the first, which is preferably, although not necessarily, inclined to the base. The effect of this arrangement is to cause the air currents 105 to flow upwardly for a short distance, and to then turn and flow downwardly into the interior of the casing. By reason of this construction the air currents are compelled to follow a zig-zag path; hence no opportunity is afforded for cross-drafts, as in the case 110 above referred to. The path of the air currents is clearly indicated by the arrows, Fig. 1.

In accordance with the provisions of the 115 patent statutes, I have described the principle of the operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is,

1. In a burner, the combination of a support, a plurality of vaporizing tubes having their inlet ends mounted on the support, a nozzle centrally located between said ends, the vaporizing tubes inclining upwardly from their inlet ends to form an apex above the 125

nozzle, a conduit leading from the apex to the nozzle, means supplying fuel to the vaporizer tubes to flow through them in multiple to said apex and conduit, and a baffle-plate 5 arranged above the nozzle and between it and said apex against which the stream of fuel from the nozzle strikes and is deflected laterally toward the vaporizing tubes.

2. In a burner, the combination of a nozzle 10 having a discharge opening, vaporizers which are spaced apart and inclined toward each other at their upper ends, a head uniting the upper ends of the vaporizers above the nozzle, a tube of smaller cross-section and more 15 easily heated than the vaporizers which is connected with the head and the nozzle to supply vapor under relatively high pressure to the latter, and a baffle-plate arranged in coöperative relation to the nozzle with its 20 periphery separated from the vaporizers by a space forming carbureting and combustion zones, said baffle-plate being so closely adjacent the nozzle that it receives the stream of vapor delivered under said pressure from the 25 nozzle unmixed with air, breaks up the stream and deflects the particles to mix with the air in the carbureting zone and burn in the combustion zone.

3. In a burner, the combination of a support, 30 a nozzle mounted on the support, a plurality of vaporizing tubes having their inlet ends disposed about the nozzle, said tubes inclining upwardly and inwardly toward an apex above the nozzle, a head which unites 35 the tubes at the apex, a conduit leading from the head to the nozzle, means supplying fuel to the inlet ends of the vaporizing tubes, and a baffle-plate arranged between the converging 40 ends of the tubes above the nozzle against which the stream of fuel from said nozzle strikes and is deflected laterally toward the vaporizing tubes.

4. In a burner, the combination of a support, 45 a nozzle mounted on the support and projecting upwardly therefrom, two vaporizing tubes having their inlet ends mounted on the support on opposite sides of the nozzle with their axes in a plane passing through the axis of the nozzle, said tubes inclining upwardly and inwardly from their inlet ends toward 50 said axis, an axially arranged head above the nozzle which unites the upper ends of the tubes, a conduit located in a plane transverse to the plane of the vaporizing 55 tubes which connects the head with the nozzle, means supplying fuel to the tubes to flow through them in multiple to said head and conduit, and a baffle-plate mounted on the head and centrally located between the converging 60 ends of the tubes above the nozzle, against which the stream of fuel from said nozzle strikes and is deflected laterally toward the vaporizing tubes.

5. In a jet burner, the combination of a 65 casing, a nozzle, vaporizing tubes connected

thereto and in multiple with each other, a body of non-conducting material surrounding the receiving ends of the vaporizers to maintain a difference in temperature between the fuel inside and outside of the casing, 70 a single source of supply connected to the vaporizers, and a baffle plate supported in close proximity to the nozzle.

6. In a burner, the combination of a casing, 75 a nozzle, an auxiliary starting burner, a supply pipe, vaporizers connected thereto and in multiple relation with each other, non-conducting protectors for the receiving ends of the vaporizers to maintain a difference in temperature between the fuel inside and outside of the casing, a tube connected to the vaporizers for conveying vapor to the nozzle, and a baffle plate supported in close proximity to the burner nozzle.

7. The combination of a burner of the jet 80 type, an inclosure therefor comprising side walls, a base plate supporting the burner which forms one or more air admitting openings between its edges and the side walls, upwardly extending baffle-plates on the base 85 plate adjacent the openings, and downwardly extending baffle-plates which overlap the other baffle-plates and coöperate therewith to deliver the incoming air to the burner and to prevent cross currents through 90 the inclosure.

8. The combination of a burner of the jet type, an inclosure therefor comprising side walls, a base plate supporting the burner which is turned upwardly within the casing 100 at one or more of its edges to form baffle-plates and coöperating with the adjacent side walls to form air admitting openings, and baffle-plates which extend downwardly from the side walls to overlap with the upwardly extending baffle-plates and coöperating therewith to direct the incoming air to 105 the burner and to prevent cross air currents through the inclosure.

9. In a jet burner, the combination of a 110 supply pipe, a casing, vertically rising vaporizers, protecting shields for the receiving ends of the vaporizers for maintaining a difference in temperature between the fuel inside and outside of the casing, a non-conducting packing for said shields, a head connecting the vaporizers, a baffle plate secured to the head, a nozzle, a tube connecting the vaporizers and head with the nozzle, and a heat protective covering for the tube.

10. In a burner, the combination of a base plate, a vapor discharging nozzle supported thereon, means for vaporizing liquid fuel, a connection extending from said means to the nozzle having the portion adjacent the nozzle disposed parallel to the base plate, an auxiliary burner which comprises a tube located below and parallel to the portion of said tube adjacent the nozzle, and means for supplying fuel thereto.

11. In a burner, the combination of a nozzle, a base, vaporizers mounted on the base with their receiving ends on opposite sides of the nozzle and their delivery ends inclined 5 toward a point centrally over the nozzle, means joining the delivery ends of the inclined portions of said vaporizer in multiple, a connection between said means and the nozzle for supplying it with vapor, a support 10 adjacent said means, and a baffle-plate on the support about the periphery of which the vaporizers are grouped at a distance therefrom, said plate being located in line with the nozzle and intermediate the receiving and 15 delivery ends of the vaporizers.

12. In a burner, the combination of a nozzle, a plurality of vaporizing tubes extending upward over the nozzle and inclined toward

each other, a head uniting the upper ends of the inclined tubes at a point centrally over 20 the nozzle, a vapor-carrying conduit leading from the head to the nozzle, a stud projecting downward from the head, and a circular baffle-plate on the end of the stud about 25 which the vaporizing tubes are grouped which is of less diameter than the space between said tubes, said plate being located centrally over the nozzle at a short distance therefrom.

In witness whereof, I have hereunto set 30 my hand this sixth day of June, 1903.

HERMANN LEMP.
